CLAIM

The ornamental design for a coordinate input device, as shown and described.

DESCRIPTION

FIG. 1 is a front bottom left perspective view of a coordinate input device showing my new design;

FIG. 2 is a rear top right view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is an enlarged view of a portion of the coordinate input device shown in FIG. 1;

FIG. 10 is an enlarged view of a portion of the coordinate input device shown in FIG. 2;

FIG. 11 an enlarged view of a portion of the coordinate input device shown in FIG. 3; and,

FIG. 12 is an enlarged view of a portion of the coordinate input device shown in FIG. 3.

The dashed broken lines in the drawings show portions of the coordinate input device that form no part of the claimed design. The dot-dot-dash broken lines in the drawings indicate from where the enlarged views are taken and form no part of the claimed design.
